UNITED STATES PATENT OFFICE.

SOL STASEL AND DANIEL BERWICK, OF CHICAGO, ILLINOIS; SAID BERWICK ASSIGNOR OF ONE-TWENTIETH OF THE WHOLE RIGHT TO NICHOLAS BERWICK AND ANNA E. BERWICK, OF CHICAGO, ILLINOIS.

SPARK PLUG.

1,413,625.

Specification of Letters Patent. Patented Apr. 25, 1922.

Application filed February 24, 1921. Serial No. 447,432.

To all whom it may concern:

Be it known that we, SOL STASEL and DANIEL BERWICK, citizens of the United States, residing at Chicago, in the county of

5 Cook and State of Illinois, have invented certain new and useful Improvements in Spark Plugs, of which the following is a specification.

This invention relates to spark plugs and 10 more particularly to adjustable and self cleaning spark plugs.

The primary object of the invention is to provide an improved spark plug having the electrodes arranged whereby the spark gap 15 may be lengthened or diminished, without removing the plug from its position in the motor.

Another object of the invention is to provide a spark plug of this character which 20 will have the electrodes arranged so that one of the electrodes will be stationary or fixed, while the other electrode will be movable, so that the movable electrode may be engaged with the stationary electrode whereby the 25 surface of the stationary electrode may be scraped by the movable electrode for removing any carbon which may form on the electrodes.

A still further object of the invention is to 30 provide an improved spark plug construction which will permit adjustment and cleaning of the electrodes and which will include manually operated mechanism located so as to be conveniently operated whereby the 35 adjusting and cleaning of the electrodes may be accomplished without removing the plugs from their positions in the motor.

Other objects of the invention will appear 40 upon consideration of the following detail description and accompanying drawings, wherein:

Figure 1 is a perspective view of a series 45 of spark plugs mounted in position in the head of a motor, and showing the mechanism associated with the spark plugs whereby the movable parts may be manually actuated from a point within reach of the driver's seat.

Figure 2 is a cross section through one of 50 the spark plugs, and through the mechanism for actuating the movable parts thereof.

Figure 3 is an elevation of the improved spark plug showing a modified form of the means for individual actuation of the movable parts of the plug.

Figure 4 is a detail perspective view showing the construction of the lower end of the movable electrode.

Figures 5, 6 and 7 are detail views showing different positions of the electrodes relative to each other.

Referring to the drawing by numerals, the spark plug comprises the shell 1 with the insulator 2 mounted therein, the lower end of which projects beyond the lower end of the shell as shown. The retaining bushing 3 is screw threadedly mounted in the upper end of the shell to assist in holding the insulator in position. Mounted in the lower end of the shell is the circular, stationary electrode 4 which consists of a cylindrical sleeve 5 driven into the lower end of the shell to be firmly fixed therein and provided with an annular flange which engages the lower end of the shell thus forming the circular electrode. A cylindrical bushing 6 extends longitudinally through the center of the insulator, and this bushing embraces the longitudinally movable stem 7 of the movable electrode. The stem 7 has its lower end provided with a cross arm 8, each end of the cross arm carrying a pin 9. These pins 9 form double movable electrodes which are disposed parallel to the stem 7 and extend toward the circular electrode 4. The free ends of the pins 9 are flattened, so that the terminals 10 of the pins provide scraper elements which may be moved into contact with the surface of the circular electrode 4, whereby the said surface may be scraped when the pins are oscillated.

The central sleeve 6 which extends upwardly through the insulator 2 has its upper end slightly enlarged and is screw threaded to receive a fastening bushing 11 which extends down into the insulator and is secured therein in any preferred manner. A suitable packing 12 is interposed between the bushing 11 and the sleeve 12 to tighten this connection and prevent any possible leakage through the plug. The upper end of the stem 7 extends upwardly through the top

of the sleeve and is connected to suitable mechanism adapted for manual actuation whereby the stem may be longitudinally reciprocated to move the pins 9 toward and 5 away from the circular electrode 4.

For ordinary purposes, such as use on automobile motors, the mechanism shown in Fig. 3 may be employed. In this construction the top of the insulator is provided with 10 a pair of cap nuts, mounted on the upper end of the sleeve 6, the cap nuts being indicated at 13 and 14. These nuts are spaced apart to permit the reception of a bracket member 15 which has an upstanding arm 16 15 upon which is pivotally mounted a lever 17 having a handle 18 whereby the lever may be manually operated. One end of the lever is connected by a pin 19 to the stem 7 and it will be obvious that when the lever is actuated 20 the stem 7 may be moved upwardly and downwardly whereby the double electrodes 9 will be moved toward and away from the circular electrode 4 thus varying the length of the spark gap as desired. Furthermore, 25 the lever may be actuated so as to bring the scraping edges 10 into direct contact with the surface of the circular electrode 4 whereupon the lever may be oscillated, the bracket 15 swinging around with the lever, thus imparting a turning movement to the stem 7 whereby the scraper edges 10 will movably engage the surface of the circular electrode 4 to scrape the carbon therefrom. In this manner, the surface of the electrode 4 may 30 be entirely cleaned of carbon without removing the plug from its position in the motor. It will be apparent that the movement of the movable electrode will accomplish two purposes namely, the adjustment of the 35 spark gap, and the scraping of the surface of the stationary electrode.

In order that all of the spark plugs in a motor may be adjusted or cleaned from the driver's seat, the mechanism shown in Figs. 45 1 and 2 has been provided which will be especially desirable for use in aeroplanes when anyone or more of the spark plugs in the aeroplane motor miss fire, or require adjustment.

50 As shown in Fig. 1, the movable stem 7 in each spark plug is extended above the plug, a suitable coupling sleeve 20 being provided to form the extension. A longitudinally extending shaft 21 is mounted upon suitable 55 standards or brackets 22 and this shaft has right angularly extending rocker arms 23 fixed to the shaft in any preferred manner, and adapted to be connected, as indicated at 24 to the upper ends of the movable stems 7. 60 An operating arm 25 is connected to the shaft 21 and extends outwardly at right angles therefrom and has its ends joined to a movable connecting arm 26 which in turn is connected to a crank arm 27 on the shaft 28. 65 The shaft 28 projects through a suitable

opening in the dash board, directly in front of the operator of the vehicle or aeroplane, and a handle 29 is provided whereby the shaft may be actuated. Manual operation of the handle 29 will cause the series of movable connections to impart a turning movement of the shaft 21 whereby the rocker arms 23 will swing to move the movable electrode upwardly and downwardly for accomplishing the same purpose that it accomplished by the movable lever 17 in the above described individual form.

For imparting the turning movement of the movable stems whereby the electrodes may be cleaned, the arms 30 are connected 80 to the movable stems 7 and extend outwardly therefrom so that their outer ends may be connected to a connecting member 31 which may be moved to cause the arms 30 to move simultaneously. The end of the connecting 85 member 31 is joined to an operating rod 32 which extends through an opening in the dash board within convenient reach of the operator whereby he may actuate the rod 32 to cause movement to be imparted to the 90 member 31 whereby the arms 30 may be oscillated. The arms 30 should be long enough to permit a half circular movement, thus causing the scraper element 10 to scrap the entire exposed surface of the fixed electrode 95 to thoroughly clean the carbon therefrom. Suitable battery connections 33 are provided in this form of arranging the plugs so that the wires 34 from the battery may be connected to the spark plugs in the usual manner. This arrangement of the mechanism 100 may be employed either on an ordinary automobile motor, or on an aeroplane motor, the purpose being to permit adjustment and cleaning of the spark plugs from a point 105 within convenient reach of the operator of the vehicle or aeroplane.

In Figs. 5, 6 and 7 I have illustrated the relative positions of the electrodes when the adjustments are made. In Fig. 5, the points 110 of the double electrodes are within very close proximity to the movable electrode 4 so that the motor may be readily started with a minimum quantity of gas. It is well known that a larger spark is desirable after the motor 115 has been started. By igniting a greater quantity of gas, the compression within the cylinder is more complete, and it necessarily follows that less carbon will form. The small spark is sufficient for igniting and exploding the gas when the motor is started, but since a greater volume of gas is ejected into the cylinders after the motor has been started, it is desirable to increase the spark 120 to complete the combustion of the larger volume of gas and also to quicken the explosion. This is accomplished by manually moving the mechanism to actuate the movable stem 7 whereby the cross arm 8 will move downwardly to move the electrodes 9 125 130

away from the stationary electrode 4 as shown in Fig. 6. Obviously any length of spark may be obtained by this adjustment.

- When it is necessary to clean the electrodes, especially the lower surface of the circular electrode, it is merely necessary to actuate the lever 17 or the lever 29 so that the edges 10 are moved up into contact with the surface of the stationary electrode 4.
- 10 Then by turning the actuating mechanism so as to oscillate the stem 7, the electrodes will scrape the surface of the electrode 4 and clean any carbon therefrom.

What is claimed is:—

- 15 1. In combination with a spark plug mounted in a motor cylinder, a fixed electrode, a movable electrode arranged on the said plug and disposed within the cylinder, and manually operated means mounted upon the motor and engageable with the movable electrode at the top of the spark plug whereby the said means may be actuated to move the said movable electrode, relatively with respect to the said fixed electrode with-
25 in the cylinder.
2. In combination with a series of spark plugs mounted in a motor, a fixed electrode for each plug, a movable electrode, a stem extending through each plug and connected 30 to each movable electrode whereby the electrodes may be adjusted with respect to each other when the stem is actuated, and manually operated means mounted upon the motor and within reach of the operator of the
35 motor and connected to the said stems whereby all of the electrodes may be simultaneously adjusted when the said means is actuated.
3. A spark plug having a body, a fixed electrode mounted in the lower end of the body and having a circular flat sparking surface, a central rotatable and longitudinally adjustable stem mounted in the body, a bracket rotatably mounted on the body, an

operating lever pivoted to the bracket intermediate the ends of the levers and connected at one end to the said stem, the opposite end of the lever forming a handle, a cross arm fixed to the lower end of the said stem, and pins carried by the said cross arm in parallel relation to the said stem, and equipped with flattened ends to form scraper elements adapted to move toward or away from said circular sparking surface and be oscillated across the said surface when the operating lever is simultaneously rocked and turned.

4. In combination with a series of spark plugs mounted in a motor, a fixed electrode for each plug, a central rotatable stem also adapted for vertical reciprocation, movable electrodes carried by the lower ends of the said stem, a shaft mounted upon the motor above the said plugs, rocker arms carried by the said shaft and attached to the upper ends of the said stems, and means to manually actuate said rocker arms.

5. In combination with a series of spark plugs mounted in a motor, a stationary electrode for each plug, including a circular sparking surface, a rotatable stem mounted centrally in the plug and adapted to be rotated and also arranged for vertical reciprocation, movable electrodes carried by the lower ends of the said stem, a shaft mounted upon the motor above the said plugs, rocker arms carried by the said shaft, extensions carried by the said stem, to connect the stems with the rocker arms, means to manually actuate the said rocker arms, laterally extending arms attached to the stems, a connecting member for the said arms, and an operating rod connected to the said connecting member, and adapted to be manually reciprocated.

In testimony whereof we affix our signatures.

SOL STASEL.
DANIEL BERWICK.
